SAFETY LOCK

Herbert Gudge, New York, N. Y.

Application February 15, 1938, Serial No. 190,542

2 Claims. (Cl. 70—277)

The purpose of this invention is to provide a keyless combination lock for motor vehicles, by which the door lock may be released when one forgets the key, or locks the key on the inside.

5 The invention is a lock, preferably positioned under the hood of a motor vehicle, to be used only in case of emergency, and this has a double combination in that every car owner may set his own combination, and then, if he forgets his key, 10 he may raise the hood, turn the lock to the proper position, press a button and release the door lock, and this may also be provided with means whereby anyone unfamiliar with the lock will cause the horn to blow as soon as he starts tampering with the lock.

15 Automobile locks of different types and designs have been provided and used in various positions, however, this device is not a lock but is merely a releasing means which cooperates with the door lock when the door is locked with the key on the inside, thereby making it possible to open the door by setting the combination to a certain position.

20 The object of this invention is, therefore, a simple and unique combination emergency lock which may be used by the owner of the vehicle to open a door when the key has been locked on the inside or misplaced.

25 Another object is to provide a combination emergency lock adapted to unlock the door of motor vehicles in which the combination may be changed as desired.

30 Another object is to provide means for opening the door of a motor vehicle when the key has been locked on the inside, by which the door may be opened without a key.

35 Another object is to provide means for opening the door of a motor vehicle with the key on the inside thereof, which will sound an alarm when tampered with by anyone except the owner thereof.

40 A further object is to provide a combination lock for motor vehicles which may be located under the hood, and which may be set to release a door by pressing a button.

45 And a still further object is to provide a combination lock for releasing the door lock of a motor vehicle in an emergency, such as when the key has been locked on the inside or misplaced, which is of a simple and economical construction.

50 With these ends in view the invention embodies an emergency combination lock which may be opened by a key to set the combination thereof, which may be set by hand to an operating position, and then a part thereof moved inward to 55 complete a circuit which may release the lock of

a door, and which is connected in the horn or an alarm circuit of the vehicle to give an alarm when operated by one not familiar therewith. The device may also have a light enclosed by which the operation thereof may readily be observed.

5 Other features and advantages of the invention will appear from the following description taken in connection with the drawing, wherein:

Figure 1 is a view showing a front elevation of the lock.

10 Figure 2 is a cross section through the lock taken approximately on line 2—2 of Figure 1.

Figure 3 is a view similar to that shown in Figure 1 with the front portion omitted, and showing the interior operating mechanism.

15 In the drawing the lock is shown as it may be made, wherein numeral 1 indicates the main case, numeral 2, the cap or cover, and numeral 3, an operating knob.

20 The part 1 is preferably made of a thin shell with a base plate 4, and the cap 2 is hinged to this part by a hinge 5 and locked in place by a lock 6, as shown in Figure 2, with the bail thereof extending through projections 7 and 8 on the cap and case respectively. However, it 25 will be understood that this lock may be incorporated in the case and opened and closed by a key through a key-hole 9 shown in Figure 1, in which the lock is incorporated inside of the cap and case. The face of the cap 2 is provided with 30 windows or openings 10 and 11 through which pointers 12 and 13 may readily be observed, and the pointers are mounted upon a shaft 14 which extends through an opening in the center of the cap 2, and the knob 3 is attached to the outer 35 end of the shaft as shown.

25 The pointer 12 is mounted on the shaft through a sleeve 15, and this may be rotated by a knurled nut 16, and, as it is rotated, it will turn a pointer 17 which extends downward into an opening 18 40 in an insulating disc 19 pivotally mounted on a bearing 20 of the base 4, and it will be noted that, as this is turned, it will turn the disc 19 to adjust the position of contact points 21 and 22 45 on segments 23 and 24, and by this means the combination is changed, and may readily be changed from time to time. In order to turn these parts, it is necessary to unlock the cap 2 and raise it about the hinge 5, as, with the cap in place, these rotating parts are completely enclosed, whereas, with the cap opened and the knob 3 removed, it is possible to rotate the pointer 12 and the disc 19 by the knurled nut 16. The upper plate 25 of the base 1 may be provided with graduations 26 so that the pointer 12 may 55

be set with the contacts 21 and 22 in various positions, and these positions may be determined without opening the base 1.

A circuit is completed across the contact points 21 and 22 by a brush 27 on an arm 28, and the arm is mounted upon the shaft 14 and held in position by a set screw 29 by which the position thereof may be adjusted, and it will be noted that, as this member is turned to such a position 10 that it will engage the points 21 and 22, the knob 3 may be pressed inward to move the member 27 against the points 21 and 22 to complete a circuit therethrough, and, as soon as it is released, the knob and shaft will be returned to 15 the position shown, by a spring 30 in the socket 20.

The pointer 13 is also mounted upon the shaft 14, and this may also be adjusted to different positions by a set screw 31, and this pointer may 20 be observed through the opening 11 in the cap 2, so that it may be set to a graduation on a dial 32 on the face of the plate 25, and the position of this pointer in relation to the pointer 12 must be known to the operator of the vehicle in which 25 the device is used.

The contact points 21 and 22 may be connected in a circuit to the lock of the door of the vehicle, as indicated in Figure 3, and this may be formed with wires 33, 34 and 35 connected to a solenoid 30 36 through a battery 37, and, as the solenoid is energized, it will raise a lever 38 and release the lock bar 39 which forms a latch of the door, a portion only of which is shown, and this is indicated by the numeral 40, with the regular door 35 handle indicated by the numeral 41. It will be understood, however, that this releasing mechanism may be of any type or design, and may be arranged in any manner. As there are many different types of door locks, an attempt is not 40 made to illustrate any particular form of lock, however, a lock may be incorporated in the handle 41, and a movable part of the lock may be provided with a projection extending into a notch in the lever or bolt 39, as it will be noted that, 45 when the lock is released and the handle turned, this projection will draw the bolt inward and release the door; however, with the door lock in the handle 41 locked, the inner end 38 of the bar 39 may be raised by the electromagnet 36 50 so that it is released from the lock 41, and the door may then be opened.

The device is also provided with another circuit to the horn of the vehicle, or this may be connected to a bell or any suitable means for giving an alarm, and this circuit is operated by 55 a brush 42 on the arm 28, and, if this brush is turned in either direction, it will engage one of the contacts 43 and 44 which are connected to a wire 45 and a battery 46 to a horn 47, with the 60 opposite terminal of the horn connected to the brush 42 by a wire 48. This is a safety circuit, and is not used by the owner of the vehicle, as, in his operation thereof, he only turns the knob to the correct position, whereas anyone not familiar with the combination will turn the knob, and, if it is turned beyond certain limits, the ends 65 of the brush 42 will engage one of the contacts

43 or 44, and thereby cause the horn to blow which will give an alarm. It will be understood that this circuit may also be arranged in any manner, and any means desired may be used for sounding an alarm, with the thought that, when the alarm is sounded, anyone tampering with the device will immediately leave the vehicle and attempt to escape. 5

The lock may also be provided with a small, electric light 49 which may be connected to any 10 suitable circuit of the vehicle, and which may be operated by a button so that, when it is desired to set the pointer 13 in the dark, it is only necessary to press the button to light the light 49 which will illuminate the entire interior of the 15 cap so that both dials may readily be observed. It will be understood that this light may be located at any suitable point, and may be operated by any means, and also that any means may be used for illuminating the lock to facilitate operation thereof. 20

It will be understood that changes may be made in the device without departing from the spirit of the invention. One of which changes may be in the use of a combination lock of any 25 standard design having contact points that may be arranged to accomplish the same result, another may be in the use of other means for connecting the lock as shown and described to the door lock, and still another may be in the use 30 of other means for setting the combination lock to any position, and also for operating the lock at any position.

The construction will be readily understood from the foregoing description. In use this device is preferably installed at any suitable point under the hood of the vehicle, and is only used when the operator thereof forgets or loses his key, or locks the key on the inside, and then, in order to open the door, it is only necessary to raise the hood, turn the knob 3 until the pointer 13 is in the proper position, and then press the knob, and, when the knob is pressed, a circuit will be completed which will release the door lock. 40

Having thus fully described the invention, what I claim as new, and desire to secure by Letters Patent, is:

1. In combination with a motor vehicle having a door with a lock therefor, a combination emergency lock, a casing in which the lock is incorporated, a cover for said casing, means locking said cover in the closed position, means for setting the combination of the lock with the cover open, and suitable circuits connecting the lock to means releasing the door lock, said combination emergency lock adapted to be set to release the said door lock. 50

2. In combination with a motor vehicle having a door with a lock therefor, a combination emergency lock, and suitable circuits connecting the lock to means releasing the door lock, in which the operating circuit is controlled by a contact point which may be set to a certain position, and then moved to engage contacts from the exterior of the casing, said combination emergency lock adapted to be set to release the said door lock. 60
